UNITED STATES PATENT OFFICE.

LINNAEUS T. SAVAGE, OF NEW YORK, N. Y.

DESIGN FOR A MATCH-BOX SUPPORT.

No. 39,434.

Specification for Design.

Patented July 28, 1908.

Application filed April 2, 1908. Serial No. 424,831. Term of patent 7 years.

To all whom it may concern:

Be it known that I, LINNAEUS T. SAVAGE, a citizen of the United States, and a resident of New York city, in the county of New York and State of New York, have invented a certain new and useful Improvement in Designs for Match-Box Supports, of which the following is a specification, reference being had to the accompanying drawing, forming part hereof.

As shown in the drawing, the design, in its leading or material features, consists of a match-box support in the form of, or a representation of a cream-separator, with a pedestal A, outlines of the bowl-container B and the superposed catchers C and spouts D, with the pan-supporting arm E and arm F. The recentacles G H are for matches and

burned matches, and are attached to the arms (or are shown as though they were attached to the arms) E F.

In practice, I print and cut out the design and attach the boxes G H thereto in any suitable manner.

Any suitable or desired colorations may be used on the various parts of the design. The crank arm I, feed-regulator K, lubricator L, and gear casing M are also shown.

I claim—

The ornamental design for a match-box support, substantially as herein shown and described.

LINNAEUS T. SAVAGE.
